VEHICLE ROOF STRUCTURE

George Trautvetter, Philadelphia, Pa., assignor
to Edward G. Budd Manufacturing Company,
Philadelphia, Pa., a corporation of Pennsylvania

Application January 16, 1934, Serial No. 706,796

1 Claim. (Cl. 296—137)

My invention is a roof structure, particularly of the all-steel variety, for automobiles and the like, and it has for its objects the more effective sealing of such a paneled roof, rendering it neater in appearance, facilitating fabrication, spot welding and assembly, preventing drumming, and providing a structure that shall be simple and durable in construction, economical to manufacture and effective in its operation.

With such objects in view, as well as other advantages which may be incident to the utilization of the improvement, such as preventing corrosion, precluding ready injury by tearing, as in fabric roof panels, facilitating mounting of the upholstery and rendering repair easier, the invention consists in the parts and combination thereof hereafter set forth and claimed, with the understanding that the several necessary elements constituting the same may be varied in proportion, arrangement and texture without departing from the spirit and scope of the invention.

In particular, the body of a car has a sheet metal roof header comprising, as is usual in this practice, a sheet metal die stamping having an outer perimeter, merging through gradual curves between the upright sides and the roof contour of the body, the header being, in top-plan view, on the order of a closed loop having a central aperture of generally rectangular shape, for the reception of a main roof or panel; the structure, as so far generally described, being of usual construction.

However, in accordance with a preferred form of the invention, the header has, at its inner perimeter edge, a depending flange of peculiar section configuration, defining successively, from its position of departure from the regular roof configuration, a depending wall, which forms adjacent to the frame therebelow a top opening channel, then rises slightly and continues toward the center of the panel opening to form a generally horizontal shoulder below the roof level, then descends further and finally has a horizontal bottom stop or flange.

The panel of my invention is constructed similar to the outer panel of a sheet metal car door, having an outer surface shaped to the contour of the roof and an outer edge flange crimped about a sheet metal frame or element of Z-section whereby a laminating outer edge of relatively thin, but strong, section is adapted to lie over the above mentioned channel and shoulder of the inner frame flange in flush relation to the header but spaced therefrom entirely about its perimeter. The middle leg of the Z-section forms a wall op-

posite a corresponding wall of the frame, but in spaced relation thereto, and has an inner or bottom leg or flange adapted to rest on, and be secured to the inner horizontal flange of the frame, as by nuts and bolts, where it is desired that the panel be easily removable, but preferably by spot welding for which this structure is particularly well adapted.

A seal element, preferably in the form of a ring or frame of adhesive material, such as a plastic non-hardening weather-proof cement, several such cements being on the market as commercial products, one of them being known as "Dum-Dum", is placed between the adjacent cooperating frame and panel edge surfaces, and has a section of substantially Z-shape including a portion in the top space between the header and the roof, a horizontal arm in the header channel and over the shoulder, and an upright leg between the aforesaid walls of the header and the roof. The panel thus contacts the frame only at its bottom portion, inwardly of the outer surface of the header, against the bottom flange of the frame, and the extreme edge flange of the panel presses downwardly against the sealing element to force it into the channel and in and about the adjacent parts; this sealing material being chosen to form, when set, a permanent bead or sealing edge between the spaced adjacent edges of the frame and the panel.

Cross channels and adherent sheets of sound-deadening material are also preferably formed on the under surface of the panel, to prevent drumming, and to permit mounting the ceiling upholstery on the channels. The structure renders the roof frame and the panel readily manufacturable by simple dies and simple stamping operations, facilitates spot welding the parts, renders the panel an entirely separate and complete unit, which need not be mounted until the car body has been assembled, insures a perfect and durable seal, facilitates repair, enhances the appearance of the vehicle to a high degree, renders the roof soundproof, conduces to ready mounting of the upholstery and has other advantages.

The invention will be better understood from a consideration of the following description and the accompanying drawing, in which:

Figure 1 is a top plan view of an automobile roof structure embodying the invention;

Figs. 2, 3 and 4 are views taken along the lines 2—2, 3—3 and 4—4 of Fig. 1; Fig. 4 showing a slight modification of the invention, and

Fig. 5 is a view similar to Fig. 2, of a substantial modification of the parts.

A header 6, preferably of sheet metal, such as sheet steel, is generally of rectangular plan contour having widely rounded corners, and of a usual bowed contour in elevation; the central or panel-receiving opening thereof also being of round-corner generally-rectangular plan contour, but having the sides slightly curved, as are the sides of the header, in accordance with a present style.

As seen more clearly in Fig. 2, the inner perimetral edge of the header 6 has a depending flange of peculiar conformation, generally of Z-section, dropping into a top opening channel 7, then rising and extending along a shoulder 8 not so high as the top of the frame, then descending through a wall portion 9 and terminating in a bottom horizontal shelf or step 10; this configuration requiring simple dies and effectively working the metal.

The panel comprises a top layer 12, substantially flush with the top surface of the frame 6 and having an edge margin 14 crimped downwardly around its perimeter and back along the contour of the roof about one leg 15 of an element of Z-section, which further comprises a middle leg or wall 16 spaced opposite the wall 9 and a bottom step or flange 17 resting on the shelf 10; this structure also being along simple die stamping lines, requiring only simple dies and working the metal to advantage.

In the proportion and relation of the parts shown, the top layer or metal roof panel 12 is held outwardly in position by the metal-to-metal engagement between the parts 10 and 17 with the outer face thereof a smooth continuation of the contour of the outer face of the adjacent header 6, but, in outer perimetral contour, the panel is substantially smaller than the adjacent parts of the frame, whereby to accommodate a substantial body 18 of a thick adhesive sealing material.

In mounting the panel, the material 18 is placed generally in position about the frame, to a quantity such that it will be pressed by the panel into close adherence and conformity to the adjacent parts downwardly for a limited distance between the jamb wall portions 9 and 16, downwardly into the channel 7 and upwardly between the outermost adjacent edges between the panel and the frame. By providing the channel 7, it has been found that the sealing material 18 forms a more perfect seal free from blobs or fissures and insures that at least one entire perimetral zone of the sealing material will be liquid tight; the reason probably being that, when the sealing material is once pressed downwardly into the bottom of the channel 7, subsequent movement of the panel in the roof plane, if such movement occur or be necessary in effecting slight adjustments of the panel, the material at the bottom of the channel does not move, and, being of a tenacious character, clings to the remainder thereof which may tend to

move. Also, the increased body or bulk of the material at the channel probably reduces stresses in it and provides a volume thereof by which, under pressure, it readily chokes the adjacent narrower passages thereto. It is provided in such quantity, and is of such character, that it will preferably press a substantial distance downwardly between the jamb walls 9 and 16, and remain clear of the engaging surfaces of the parts 10 and 17, which are spot welded, or otherwise secured.

Channel elements or beams 19, which may be filled with wood 20, or other material, as indicated in Fig. 3, are provided to prevent drumming of the sheet metal panel, and also, to constitute bases upon which elements 21, for holding an upholstery layer 22 may be secured to the beams, as by tacks 23; a heavy paper layer 24 also being provided between the panel layer 12 and the beams 19, and secured in position, as by a heavy asphaltic or other adhesive material adhering to the steel and to the paper.

As shown in Fig. 4, instead of being spot welded to the shelf 10, the step 17 is removably secured thereto, as by spacer nuts 26, lock washers 25 and bolts 28, this construction being a modification by which the panel may more readily be removed. The side of the channel 7 adjacent to the layer 6 together with the bottom of the channel and the shoulder 8, form a structure of substantially L-section, as do the parts 9 and 10.

In Fig. 5, portions 29 and 30, forming the upright and horizontal arms of a simple L-section, receive a panel 31, which is also of simplified section, having merely a right-angle flange 32 at its outer perimetral edge. The flange 32 may be spot welded to a rim member 35 of L-section, thus forming a flange corresponding to the flange 17 and resting on the flange 30.

What I claim is:

In a vehicle, a sheet metal roof-supporting header of double angle, vertical cross-section providing upper and lower rabbets with vertical and horizontal walls, the upper rabbet having a top-opening channel in the horizontal bottom wall next the side wall, a sheet metal roof panel having a marginal edge lying in the said upper rabbet with its upper surface flush with the upper surface of the header and its peripheral edge and lower marginal surface spaced away from the vertical and horizontal walls, respectively, of the upper rabbet, a depending portion on the roof panel resting directly on the bottom horizontal wall of the lower rabbet with its peripheral edge portion spaced away from the side wall of the lower rabbet, said relation of parts forming a Z-section space between the header and the roof panel, and a thick Z-section body of adherent waterproof material filling the said top-opening channel, sealing the Z-shaped space between the header and the roof panel and extending vertically upwardly between the vertical wall of the upper rabbet and the peripheral edge of the roof panel to the outer face of the roof.

GEORGE TRAUTVETTER. 65
